UNITED STATES PATENT OFFICE.

EDWIN M. CARHART, OF PROVIDENCE, RHODE ISLAND.

CAR-FENDER.

SPECIFICATION forming part of Letters Patent No. 540,632, dated June 11, 1895.

Application filed October 5, 1894. Serial No. 524,991. (No model.)

To all whom it may concern:

Be it known that I, EDWIN M. CARHART, of the city and county of Providence, in the State of Rhode Island, have invented a certain new and useful Improvement in Car-Fenders; and I declare the following to be a specification thereof, reference being had to the accompanying drawings.

Figure 1 is a side elevation of my invention when not in use. Fig. 2 is a side elevation of the same when in operation. Fig. 3 is a plan view as seen on line xx of Fig. 2. Fig. 4 is a view, partly in side elevation and partly in longitudinal section, of the actuating-spring and its connections. Fig. 5 is a cross-section on line yy of Fig. 4. Fig. 6 is a cross-section on line zz of Fig. 3. Fig. 7 is an end elevation of a car provided with my invention. Fig. 8 is an elevation of the screen which is attached to the dashboard of the car. Fig. 9 is a top view of the dashboard and said screen in position. Figs. 10, 11, and 12 are detail views.

Like numerals indicate like parts.

My invention relates to the guards or fenders used upon electric or cable cars as a protection against the injury of persons with whom such cars come into collision; and it consists of the novel construction and combination of devices, by which a pivotally mounted frame, suspended beneath the car, is provided with a netted fender which slides in said frame and which is actuated in a forward direction by springs, released from compression by the withdrawal of pins, through the action of levers, operated by the motor-man, as hereinafter particularly described and specifically set forth in the claims.

In the drawings, 1 is the body of the car, 2 the platform, 3 the wheels, 4 the dashboard, 5 the buffer, 6 the posts to support the dashboard, 7 the brake, 8 the steps, 9 the draw-bar, and 10 the cross-bar, all of the usual construction.

11, 11 are the rails on which the car travels. Upon the beam of the car platform 2 are fastened supporting pieces 12. A grooved or flanged bar 13 is pivotally mounted at 14 to the support 12 on both sides of the car. The bars are thus capable of a vertical rocking or tilting movement upon the pivotal bearings,

but the limits of its vertical oscillation are determined by pins 141, extending therefrom and entering slots 15 upon guide bars 16, which are fastened to the car body or platform 55 and confine the tilting bar 13 to a strictly vertical movement. A tube 17 is secured to the under side of the bar 13 by metallic straps 18, or otherwise, and the rear end of said tube is covered by a screw cap 19. In the 60 tube 17 is a sliding rod 20, having a head 21 and surrounded by a spiral spring 22, which has its bearing at one end against the head 21 of the rod 20 and at the other end against the cap 19. The forward end of the tube 17 65 has a central opening of a less diameter than that of the head 21 of the rod 20. In the groove in the tilting bars, formed by the flanges thereof, are mounted, on each side, respectively, the side pieces or frames 23 of 70 the car fender. These are so loosely mounted in said grooves as to easily slide therein. Cross-bars 24, 25, extend between the side pieces or frames 23, from side to side, and between said frames and cross-pieces is 75 stretched the netting 26 of wire or rope. Side guards 27, which are also netted, are fastened to the frames 23, and extend downward on each side, at an angle. A rod 28, is fastened through a bend thereof by bolts 29 to the 80 under side of each frame 23 and extends longitudinally to the rear and parallel to the frames 23. The rear end of the rod 28 is adapted to enter the opening at the forward end of the tube 17.

On each frame or side piece 23 is a truck wheel 30, having a grooved periphery, in which is mounted a rubber tire 31. This wheel is made fast to a shaft 32, which turns in the bearing 33 and the latter is bolted through a 90 flange thereof 34, to the under side of the frame 23 on each side. A sprocket wheel 35 is fastened to the opposite (inner) end of the shaft 32. The head of said shaft 32 and the nut 36 thereon keep the wheels 30, 35, in 95 place. At the front ends of the frames 23 are tubular bearings 37, in which the roller 38 is journaled. The roller 38 has sprockets 39 and a chain 40, the links of which operate the sprockets. The chain 40 is crossed, as indicated at 41, by the dotted lines, so that the roller 38 is rotated in a direction opposite to

that of the rotation of the wheel 30. The chain 40 passes over the sprockets 35 and 39. The top edges of the frame 23 are provided with ratchets or notches 42 and on each side 5 of the car, pawls 43, pivotally mounted on the supports 12, have their free ends in engagement by the force of gravity with one of said ratchet teeth 42. The pawls 43 are lifted out of engagement with the ratchets 42 by means 10 of the rod or pull 44. Said rod 44, is kept normally extended forward by the spiral spring 45 surrounding it, which is attached to the car bottom at one end and has its opposite end bear against a collar 46 upon said 15 rod. At the inner end of the pull rod 44 two levers 47, 48, are pivotally connected, having their fulcrums at 48. At the outer end of each lever 47 and loosely connected therewith is a downwardly projecting bent arm 481, whose 20 lower end is loosely connected with the pawl 43. When the rod 44 is drawn outwardly it causes by these intermediate levers and arms the upward movement of the pawls and lifts them out of the ratchets 42.

25 A presser rod 49 passes loosely through the hole 50 in the platform. Its bottom is loosely fitted in or connected with two levers 51 (see Fig. 12) which are fulcrumed upon supports 52. The rear end of each lever 51 is bent downward 30 and there provided with ear pieces, between which a swinging pin 53 is pivotally mounted. (See Fig. 10.) The lower end of the pin 53 is received in a socket plate, 54, on or behind the cross-bar 24, of the fender. A stop 55 is 35 secured to the car bottom and when the fender is in the position shown in Fig. 1, its cross-bar 24 lies just beneath said stop 55. (See Figs. 1 and 11.)

40 The screen 56 is curved in its upper portion (Figs. 1 and 2) and has a central open space from its top downward to a considerable distance (Fig. 8) to allow room for the buffer 5 and also for a head light, when desired. Its bottom is about on the line of the 45 cross-bar 10 and said screen is fastened to the dashboard 4 by ear pieces and screws 57, (Figs. 8 and 9.)

45 Having thus fully described the several parts of my device I will proceed to explain 50 its operation.

55 When the device is not in use, it occupies a space under the car platform 2 and between the steps 8, as shown in Figs. 1 and 7, and so is entirely out of the way, presenting nothing 60 which is liable to do injury or to be injured. In this position, the rod 28 on each side of the frame 23 is in place within the tube 17, as seen in Fig. 4, and the spiral spring 22, around the sliding rod 20, is compressed, as there 65 shown. The pins 53 in the socket plates 54 of the cross-bar 24 counteract the pressure of the spiral springs 22 and prevent them from pushing the fender out of that position. The stops 55 prevent the rise of the cross-bar 24 of the fender. It is in this position of the several parts that the car usually travels and it

is seen by Figs. 1 and 7 that the device is wholly lifted above the rails 11, whether the car is in motion or not; but when a collision is imminent and it is desired to use the fender, the motorman, standing at the front dashboard as usual, simply presses with his foot the presser rod 49. This movement causes the rear ends of the lever 47 to rise, thus withdrawing the pins 53 from the socket plates 54 of the cross-bar 24 of the fender. The springs 22 in the tubes 17, being now no longer held 70 from action as heretofore by said pins 53, instantly expand and move the sliding rods 20 with great force and rapidity, which rods drive 75 out from the tubes 17 the rods 28 of the frames 23 of the fender. The fender thus actuated, slides easily by its frames 23 in the grooves of the tilting bars 13, and, as soon as this movement begins the weight of the fender 80 causes the bars 13 to tilt, so that they extend in an angular direction forward, thus accelerating the movement of the frames 23 sliding therein, and directing the fender downward, so that the wheels 30 come into rolling 85 contact with the rails 11. The device is then in the position shown in Fig. 2. The pawls 43, then resting in the innermost of the ratchets 42, prevent any inward movement of the car fender and resist any inwardly directed 90 pressure. The roller 38, as will be seen by examining Fig. 2 is in a position slightly above the rails. The revolution of the truck 95 wheels 30 upon the track, caused by the forward travel of the car, turns the sprocket 100 wheel 35, attached to the shaft 32. The chain 40, mounted thereon and crossed in direction, as at 41, rotates the sprockets 39 of the roller 38, but in a direction opposite to that of the rotation of the truck wheels 30, so that any 105 person or object, with which said roller 38 comes into contact, will be thrown upon the netting 26 of the car fender. The side guards 27 protect from the danger of being struck 110 by the wheels or step of the car.

110 When the fender has done its work, it is returned to its former position by hand. The rod or pull 44 is drawn outwardly and thereby the levers 47 are moved, which by the bent arms 48 raise the pawls 43 out of engagement 115 with the ratchets 42 of the frames 23 of the car fender. The fender is then pushed inwardly under the car, while the pawls 43 are thus elevated, until the cross bar 24, pushing back the swinging pins 53, passes said pins 120 and comes beneath the end of the stops 55, whereupon said pins drop by gravitation into the socket plates 54 again. This movement of the fender at the same time causes the rods 28 of the frames 23 to enter the tubes 17 and 125 to crowd back the sliding rods 20, thereby compressing the springs 22, as before, which springs are held in said compressed position by the locking device or pins 53, as aforesaid.

130 The roller 38 may be covered with rubber or other soft substance. The rubber tires 31 on the truck wheels 30 also have a yielding

function to relieve the person from a forcible shock by the fender. The netting 26 and the dashboard screen 56 all furnish a soft and yielding surface to receive the person, who is 5 rescued from the danger.

This apparatus is set in motion simply by the pressure of the motorman's foot upon the presser rod 49. All the subsequent movements of the device are wholly automatic until its work is done. The return of the device to its former inner position is accomplished by the pulling of the rod 44 to raise the pawls 43 and by pushing the fender inwardly so that its frames or side pieces 23 10 slide in the grooves of the tilting bars 13, until, when it reaches the end of its inward travel, the locking devices operate automatically and hold it in position, ready however for action again, as before.

20 This car fender is simple and positive in operation, cheap in construction, efficient for the purposes intended and does not have to be carried from one end of the car to the other at the end of the route or in reversing 25 the direction of travel.

I claim as a novel and useful invention and desire to secure by Letters Patent—

1. The combination with a car, of pivotally mounted bars provided with grooves or ways, 30 and each having a tube attached thereto with a spiral spring in each tube, a fender mounted and movable on said frames and having on each of its two sides a rod adapted to enter said tube to compress said springs, respectively, and a device to hold said springs in compression, but capable, when moved, to release said springs to impel said fender along said bars, substantially as set forth.

2. The combination with a car, of pivotally mounted tilting frames, having pins at their ends and grooves on their sides, and guide bars mounted upon the car and extending downward and having slots in which said pins, respectively, are engaged, a fender mounted 45 and movable upon said tilting bars and a spring adapted, when released, to impel said fender along said tilting frames, substantially as shown.

3. The combination with a car, of pivotally mounted tilting frames, having pins at their ends and grooves on their sides, the guide bars mounted on the car and extending downward and having slots, in which said pins, respectively, are engaged, a tube attached to 55 each of said tilting bars, having a spiral spring therein, a fender mounted and movable on said tilting bars and provided with two rods adapted to enter said tubes, respectively, and to compress said springs and a device to hold said springs in compression, but adapted, when moved, to release said springs to impel said fender along said bars, substantially as described.

4. The combination with a car, of the 60 grooved and pivotally mounted tilting bars,

the fender, having frames or side pieces mounted and movable on said tilting bars, the truck wheels on which said fender is supported, the sprocket wheels, adapted to turn with said truck wheels, the roller having 70 sprocket wheels at its ends and mounted at the forward end of the fender and the chains connecting said truck wheel sprockets and roller sprockets, substantially as specified.

5. The combination with a car, of the 75 grooved and pivotally mounted tilting bars, having pins at their ends, the guide bars extending downward from the car and provided with slots, wherein said pins, respectively, engage, the fender having frames or side pieces 80 mounted and movable on said tilting bars, the truck wheels on which said fender is supported, the sprocket wheels adapted to turn with said truck wheels, the roller having sprocket wheels and mounted at the forward 85 end of the fender and the chains connecting said truck wheel sprockets and roller sprockets, substantially as shown.

6. The combination with a car, of the 90 grooved and pivotally mounted tilting bars, the tubes fastened to said bars at the inner ends, the spiral springs within said tubes, the fender mounted and movable on said tilting bars and having rods, which are adapted to enter said tubes, respectively, to compress said 95 springs, the truck wheels on which the fender is supported, the sprocket wheels adapted to turn with said truck wheels, the roller having sprocket wheels at its end and mounted at the forward end of the fender and the chains connecting 100 said truck wheel sprockets and roller sprockets, substantially as described.

7. The combination with a car, of the 105 grooved and pivotally mounted tilting bars, a fender frame mounted and movable on said tilting bars and provided with ratchets and a pawl, mounted on the car and engageable with said ratchets, substantially as described.

8. The combination with a car, of the 110 grooved and pivotally mounted tilting bars, a fender frame mounted and movable on said tilting bars and provided with ratchets, a spring adapted, when released from tension, to impel said frame upon said tilting bars and a pawl mounted upon the car and engageable 115 with said ratchets, substantially as set forth.

9. The combination with a car of the 120 grooved and pivotally mounted tilting bars, fender frames mounted and movable on said tilting bars, respectively, and provided with ratchets, a tube on each of said bars provided with a spiral spring, a rod on each of said fender frames and adapted to enter said tube to compress said spring, and a pawl mounted on the car and engageable with said ratchets, 125 substantially as described.

10. The combination with a sliding fender, mounted beneath a car and provided with ratchets, of a pawl, mounted on the car, levers and arms mounted on the car and mov- 130

able by a rod to raise the pawls out of engagement with said ratchets, substantially as specified.

11. The combination of the grooved and 5 pivotally mounted tilting bars, a fender frame mounted and movable thereon, a spring, adapted, when released from tension, to impel said fender frame along said tilting bars, a pin adapted to engage said fender frame to

confine the same against the pressure of the 10 spring and a lever, adapted, when pressed, to lift the pin out of said engagement, substantially as specified.

EDWIN M. CARIART.
